UNITED STATES PATENT OFFICE.

ARTHUR M. LYCKLAND, OF PROVIDENCE, RHODE ISLAND, ASSIGNOR TO WACHENHEIMER BROS., OF PROVIDENCE, RHODE ISLAND, A FIRM COMPOSED OF JACOB WACHENHEIMER AND SAMUEL WACHENHEIMER, BOTH OF NEW YORK, N. Y., AND HARRY WACHENHEIMER, OF PROVIDENCE, RHODE ISLAND.

VANITY-CASE.

1,248,878.

Specification of Letters Patent.

Patented Dec. 4, 1917.

Application filed May 26, 1917. Serial No. 171,103.

To all whom it may concern:

Be it known that I, ARTHUR M. LYCKLAND, a citizen of the United States, and resident of the city of Providence, in the county of Providence and State of Rhode Island, have invented certain new and useful Improvements in Vanity-Cases, of which the following is a specification.

This invention relates to a so-called vanity case, and has for its object to provide a case of this character of the size of a locket or pendant and having two receptacles nested one within the other, the outer receptacle being perforated and of cup-shape to carry a scented medium, and the inner being cup-shaped for the purpose of carrying face powder and a powder puff or other material, said inner receptacle being preferably provided with a closing lid.

20 A further object of the invention is to construct these nesting receptacles so that the inner is hinged to the outer to swing down into the outer cup and provide a closure therefor.

25 A still further object of the invention is to provide a lid for the inner cup and also a lid for the outer cup, which latter lid is adapted to close over both of said receptacles.

30 A still further object of the invention is to provide a mirror in the back of one of the lids.

The invention further consists in the hinging of both the inner receptacle and 35 the outer lid to the outer receptacle, and to provide a catch for releasably connecting the outer lid and the two receptacles together.

40 A still further object of the invention is to provide a ring or eye connected to the joint of the inner receptacle, from which the case may be suspended when used as a pendant, and by which the inner receptacle may be swung outward from the outer receptacle upon its hinge by exerting pressure upon its eye.

45 With these and other objects in view, the invention consists of certain novel features of construction, as will be more fully described, and particularly pointed out in the appended claims.

In the accompanying drawings:

Figure 1— is a perspective view illustrat-

ing the receptacles and their lids all as moved to open position.

55

Fig. 2— is a perspective view of the lid for the inner receptacle.

Fig. 3— is a plan view of the inner receptacle.

Fig. 4— is a sectional view on line 4—4 60 of Fig. 3 of the inner receptacle.

Fig. 5— shows the inner face of the lid for the outer receptacle.

Fig. 6— is a perspective view of the outer receptacle.

65

Fig. 7— is a central sectional elevation of the outer receptacle showing the inner receptacle nested thereinto and the lids closed.

Referring to the drawings, 10 designates 70 the outer receptacle which is for the purpose of carrying perfume on a scented medium 13 such as cotton or the like, and which is preferably formed round and in a dish-shape, but this casing may be made in 75 any desired shape. The side walls 11 of this receptacle are perforated as at 12 permitting the scent of the perfume to pass out therethrough.

One edge of this receptacle is provided 80 with ears 14 pierced to form a hinge, and a spring strip 15 is attached on the inner surface of the side wall thereof opposite the hinge and is provided with a presser member 16 which extends through to the outside thereof, to serve as a release for the catch, presently described.

85 An essential feature of this invention is the provision of second receptacle 17, best illustrated in Figs. 3 and 4, whose body is 90 also of a dish-shape and is provided on one edge with an integral portion bent around in the form of an eye 18 to be hinged to the eye 14 on the outer receptacle. To this hinge eye 18 is rigidly connected a ring 95 member 19, which serves a double purpose; first, as a convenient means to which a chain or other device may be attached; and second, this ring is set on a slightly inclined angle from the plane of the face of the receptacle so that when a downward pressure is brought to bear upon it the cup is caused to tip on its hinge 18 and so be raised from its nesting position in the outer receptacle.

100 The edge of the inner receptacle, substantially at a point at right angles to the hinge

member 18, is cut out as at 20, and a pin 21 is connected to the cut-out portion around which pin is bent the hinge-eye 22 of the lid 23 whereby this lid may swing down into the bezel or groove 24 and so close this receptacle tightly to prevent the powder which is carried therein from shaking out.

Another feature of this invention is that when this inner receptacle is closed down 10 into the outer receptacle it engages and presses the cotton or other perfume-carrying medium, thereby binding and holding it tightly in position in this outer receptacle preventing it from shifting and bunching 15 up when the device is being used as a pendant.

A main lid or closure 25 is provided with ears 27 by which it is hinged to the main hinge 14 on the outer receptacle and this lid 20 is provided with a catch 26 which is adapted to engage the spring bar 15 when closed, see Fig. 7, to lock all of the members in position. The inner surface of this main lid is provided with a mirror 28 which is only 25 exposed when the lid is open.

In operating my improved casing it is only necessary to press the catch 16, which releases the lid 25 to be opened by the fingers of the user to expose the mirror.

30 A small notch 29 is provided on the edge of the lid 23 in the inner receptacle, whereby it may be readily raised to expose the puff and powder which may be applied by use of the mirror. When it is desired to expose the contents of the outer receptacle it is only necessary to press downward on the eye or ring 19, which raises this inner receptacle permitting fresh material to be inserted therein if desired.

35 40 When it is desired to close the whole, the inner receptacle is swung back into position

which really serves as a closure for the outer receptacle, the inner lid 23 is then swung back to close the inner receptacle and the outer lid is swung down and its catch passed 45 through the notch to engage the catch 15 and lock the whole closed.

The foregoing description is directed solely toward the construction illustrated, but I desire it to be understood that I reserve the privilege of resorting to all the mechanical changes to which the device is susceptible, the invention being defined and limited only by the terms of the appended claims.

55 I claim:

1. A vanity case comprising a locket having two separate nesting receptacles, the outer being larger than the inner providing a chamber between the two for carrying a 60 perfumed medium, the walls of said outer chamber being perforated, and the inner receptacle being cup-shaped and hinged to the outer receptacle and adapted to swing therein to provide a closure therefor, and a closure for the inner receptacle.

2. A vanity case comprising a locket having two separate nesting receptacles, the outer being cup-shaped and perforated, the inner being cup-shaped and hinged to the 70 outer and adapted to swing thereinto providing a closure therefor, a lid for the inner receptacle, a catch for releasably connecting the two receptacles, and a member extending outwardly from the hinge whereby the 75 inner receptacle may be lifted from the outer on its hinge when released by said catch.

In testimony whereof I affix my signature in presence of a witness.

ARTHUR M. LYCKLAND.

Witness:

HOWARD E. BARLOW.
